FIG. 1 is a front elevation of a bird house, showing my new design, the rear portion being substantially the same as the front except for the omission of the stepped boss and the aperture for the perch member;

FIG. 2 is a top plan view of the bird house of FIG. 1;

FIG. 3 is a bottom plan view of the bird house of FIG. 1;

FIG. 4 is a side elevational view of the bird house of FIG. 1, both sides being identical;

FIG. 5 is a front elevation of a modified form of the bird house shown in FIG. 1;

FIG. 6 is a side elevation thereof, the opposite side being a mirror image of the side shown;

FIG. 7 is a cross section taken on line 7—7 of FIG. 5.

I claim:

The ornamental design for a bird house, as shown and described.
